TYPEWRITING MACHINE

Russell G. Thompson, West Hartford, Conn., assignor to Underwood Elliott Fisher Company, New York, N. Y., a corporation of Delaware

Application November 26, 1935, Serial No. 51,557

10 Claims. (Cl. 248—22)

This invention relates to typewriting machines, and especially to devices for supporting and securing such machines in a manner to reduce the noise resulting from their operation.

5 Much of the noise incident to the use of typewriting machines results from the magnification of the sounds of the operating mechanism by reason of the transmission of such sounds, in themselves small, through the machine-frame to the 5 desk or working surface on which the machine rests, said surface acting as a sounding board, with a resulting magnifying effect.

10 Rubber or other resilient mountings, comprising cushions of various kinds and intended to 10 insulate against such transmission, are well known. The common characteristic of these prior devices, however, is that the resilient material is under compression, resulting in an obviously inefficient structure, because the immediate increase in density increases the sound 15 and vibration transmission qualities of the material. In addition, the constant pounding to which a typewriter is subjected during use has the cumulative effect of so distorting and compacting the resilient material as to render it absolutely 20 valueless as an insulator in a comparatively short time.

25 These disadvantages are overcome in the structures disclosed in this invention, in which the resilient material is placed under tension or shear, thus lessening its density and increasing the insulating value, and continued use, up to a reasonable limit, acts actually to improve the insulating qualities.

30 In one form of this invention, rubber of suitable strength and density is vulcanized to load bearing members which are so assembled in the complete device as to present a novel, inverted bridge structure, on which the weight of the machine is carried in suspension, the rubber acting as the suspending member, and being consequently subjected to a tensional stress.

35 In a second type disclosed herein, a rubber element of novel design is vulcanized to a centrally located metal post on which the weight of the machine is concentrated, and to a metal band which encircles the rubber element so as to prevent bulging or other lateral distortion thereof when the load is applied. The lower portion of the 40 rubber element is centrally counterbored, forming a cup-shaped base, with a comparatively narrow annular area in contact with the desk top. In this type of mounting, the weight of the machine subjects the rubber element to shear, or a 45 combination of tension and shear, as the centrally

located downward thrust is opposed by the upward reaction of the annular area in contact with the desk top.

5 A novel hold-down device also disclosed herein, utilizes the principle of rubber under tension to afford a means of holding the machine firmly in contact with the desk top without presenting a channel through which shocks and sounds of operation may reach the desk.

10 The rubber element is vulcanized to an upper plate, having means for attaching to the machine, and to a lower plate, having a tapped hole to receive a headed screw, which may be inserted through the desk top from beneath. As this screw is tightened, the machine is pulled downward against the desk top, subjecting the rubber element to a tensional stress.

15 These devices are novel in design and inexpensive to manufacture. They are readily applied to any typewriter by one unskilled in mechanics.

20 The outer surfaces are smooth, and the metal parts may be attractively plated or finished. Few recesses, which might accumulate dust, are presented.

25 Other features and advantages will hereinafter appear.

In the accompanying drawing,

Figure 1 is a representation of a typewriter of the noiseless class, mounted on one type of resilient foot disclosed herein, and secured to a desk by a resilient hold-down device.

30 Figure 2 is a sectional view of a modified form of suspension type mounting.

35 Figure 3 is a substantially full-sized representation of the mountings and hold-down device of Figure 1, partially in section, to show constructional details, and the deformation of the rubber under tensile stress.

40 Figure 4 is a modified form of mounting in which the rubber is subjected to shear by the weight of the machine.

45 Figure 5 illustrates the knurled surface of the load bearing post of Figure 4.

Figure 6 is a modification of the mounting device of the type illustrated in Figure 4.

45 Figure 7 is a partially sectional, disassembled view of the mounting of Figures 1 and 3.

50 Referring to Figure 1, 20 represents a typewriter of the noiseless class, with resilient feet or mountings 21 supporting said machine at the four corners thereof, and secured to a desk 22 by a resilient hold-down device 23.

55 The feet 21, Figures 3 and 7, are constructed with a resilient unit, designated by the number 24, Figure 7, and comprising an annular rubber

ring 25, of suitable strength and density, an annular metal disk 26 and a plate 27, said plate having secured thereto, or integral therewith, a post 28 formed with a square cut gaging shoulder 29, and screw threaded extension 30. As illustrated in Figure 7, the inner diameter of annular ring 25 is greater than the diameter of post 28, as is also the diameter of a centrally located hole 31 in disk 26. Disk 26 is formed with a concentric, downwardly turned flange 32 of suitable diameter to provide a shoulder 33.

The rubber ring 25 is secured, by vulcanization or other positive means, to the disk 26 and the lower plate 27, thus forming the integrated, resilient unit 24. The area of contact of the rubber ring 25 with the disk 26 may be so proportioned as to present a structure which, while resilient, is also sufficiently resistant to side sway to prevent the lateral vibration of the machine when in use. The possibility of noise-producing contact of the post 28 with the disk 26 is precluded by this resistance to side sway, and the spaced relation of post 28 with respect to disk 26.

A cup 34, preferably of brass or similar easily worked material, is designed to receive the resilient unit 24. The inside diameter of the cup is substantially equal to the outer diameter of flange 32, to permit the wall of said flange to engage the inner wall of cup 34 with a tight, frictional grip to prevent the accidental separation of the cup and the resilient unit which, when assembled, form the complete foot 21.

The shoulder 33 of disk 26 rests on the upper edge of cup 34, and the disk and cup thereby form a bridge structure from which the machine 35 20 may be resiliently suspended, subjecting the ring 25 to a tensional stress. The depth of cup 34 is greater than the total depth of the resilient unit 24 when the ring 25 is distorted under load, 40 as shown in Figure 3, and the machine, in effect, "floats" in a rubber suspension.

The cup 34, Figure 7, is provided with a hole 35, and is preferably fitted with a flat annular disk 36 of rubber, felt or similar material which 46 prevents marring the surface on which the machine rests, and acts as an auxiliary shock and sound absorbing element. The plate 27 is formed with a groove 37 to receive a screwdriver.

The assembled foot 21 is easily attached to the machine by means of the threaded extension 30 for which a suitably tapped hole is provided in the machine base 38, Figures 1 and 3. The hole 35 in the bottom of cup 34 provides access for a screwdriver. The shoulder 29 acts as a positive gaging means to assure the correct alignment of the feet when secured to the machine.

The modification illustrated in Figure 2, employs similar construction, except that a heavier rubber ring 40, of slightly different design than ring 25, is vulcanized or otherwise secured to the upper disk 26, lower plate 27, and also to the post 28 which may be knurled to securely bond with the rubber ring. A collar 41, preferably integral with the ring 40, cushions the upper portion of post 28 against a chattering contact with the edge of disk 26, and additionally prevents side sway. The modification of Figure 2 may be subjected to a heavier load than the form previously described in Figures 3 and 7, because of the 70 greater contact surface or bond between the rubber and the metal parts.

A second modification of the resilient foot 21 is shown at Figure 4, in which a central metal post 42, preferably knurled, as shown in Figure 5, 75 having a comparatively large diameter gaging

shoulder 43, and a threaded extension 44 by means of which the foot may be secured to the machine, is inserted into an annular rubber ring 45, which has a counterbored portion 46 of diameter substantially equal to that of shoulder 43. The outer edge forms an annular base 47. A screw 48, formed with a head 49 which may be equal in diameter to that of shoulder 43, is inserted into a suitably tapped hole in post 42, and securely tightened therein. An outer band 50 10 preferably of brass, and with an inner diameter slightly smaller than the ring 45, is forced over said ring to prevent the lateral distortion thereof when subjected to the weight of the machine. The rubber ring 45 is then bonded, preferably by 15 vulcanization, to the metal parts, forming the complete resilient foot.

In Figure 6, a simplified form of the device of Figure 4 is illustrated. A metal, central post 51, preferably knurled, formed at one end with a 20 threaded extension 52 for securing to the machine base 38 and a square gaging shoulder 53, and at the other end with a screwdriver slot 54, is inserted into an annular rubber ring 55 having a counterbored lower portion 56. A band 57, 25 similar to band 50 of Figure 4, is forced over the rubber ring, which is then vulcanized to the metal parts.

It will be seen from Figure 4 that the downward thrust resulting from the weight of the machine is centrally concentrated on the rubber ring 45, the load-bearing portion of said ring being substantially a cylinder of diameter equal to that of the shoulder 43 and the screw head 49. This downward thrust is opposed by the upward 35 reaction of the area of base 47 in contact with the desk 22. As the lateral deformation of the rubber is substantially prevented by the band 50, and as the upper and lower portions of the rubber ring 45 extend over the upper and lower 40 edges of band 50, the compression or collapse of the ring 45 is substantially limited to that portion thereof above and below the band, and the resulting stress within the ring 45 is largely shear, localized in the vertical plane of the inner wall 45 of base 47, thus causing a deformation of ring 45 as shown in Figure 4.

In the device of Figure 6, the weight of the machine, being concentrated on the post 51, is taken up by the rubber ring 55 by reason of the bond between post 51 and ring 55 resulting from the vulcanization thereof. The comparatively large diameter of the counterbored portion 56 leaves only a small bearing surface 58, and the rubber ring 55 is thus subjected to a bending moment. The natural tendency of the rubber ring 55 to pull away from the band 57 is restrained by the bond between the ring 55 and the band 57, and the rubber is thus subjected to a tensile stress. In addition, there will be a certain 60 amount of shearing stress localized in the plane of the inner wall of the bearing surface 58. In this modification, therefore, the deformation of the rubber, indicated in Figure 6, is the result of a combination of tensional and shearing stresses. 65

In the modifications of Figures 4 and 6, the cup-like formation of the lower portion results in an efficient, gripping contact, tending to prevent the "walking" of the machine, if not rigidly secured to the working surface. 70

In the hold-down device 23 illustrated in Figure 3, a block of rubber or other resilient material 60, having a centrally located recess 61 in the lower portion thereof, is vulcanized to an upper plate 62 and a lower plate 63. Plate 62 is formed 75

with a gaging shoulder 64 and a screw-threaded extension 65 by means of which the device may be secured to the machine frame 38, as shown in Figures 1 and 3. Plate 63 has a tapped boss 66 to receive a suitable headed screw 67.

When the machine 20 is equipped with the resilient mountings 21, of any of the forms described herein, and the fastening devices 23, it can be firmly secured to the desk 22, by passing the screw 67 through a suitable hole in the desk top, and inserting it in the tapped boss 66, whereupon, when screw 67 is tightened, the machine will be firmly brought down on the feet 21. The rubber block 60 of fastener 23 will be subjected to a tensile stress, causing the block to take the distorted shape illustrated in Figure 3. The expansion of the rubber lessens its density, and effectively insulates against the transmission of shocks and sounds to the desk top.

Preferably, two hold-down devices are used, one on each side of the machine, and centrally located with respect to the mountings 21.

Variations may be resorted to within the scope of the invention, and portions of the improvements may be used without others.

Having thus described my invention, I claim:

1. A shock and sound absorbing mounting for a typewriter, comprising a resilient annular ring, a stud, threaded for attachment to said typewriter, centrally disposed in said annular ring and having a comparatively large diameter head secured to the lower surface thereof, an annular disk surrounding said stud and secured to the upper surface of said ring, and a cup arranged to receive said annular ring and to act as a base by co-operating with a turned flange at the periphery of said annular disk.

2. For use with a typewriting machine, a shock and sound absorbing mounting comprising the combination of a substantially cylindrical structure carried on a protective member of resilient material, an annular disk bridging the upper end of said structure, and a stud, for attaching to the typewriter, projecting through said disk and suspending therefrom by an interponent resilient annular ring secured to said stud and said disk, said annular ring thereby insulating against the transmission of shocks and sounds by carrying the weight of said typewriter in resilient suspension from said disk, and said protective member acting as an auxiliary shock and sound absorbing base.

3. A resilient foot for a typewriter, comprising a hollow base, a member bridging said base, a headed stud extending through and beneath the bridge-member in spaced relation thereto, said stud having means for attachment with said typewriter, a ring of resilient material interposed between and secured to said bridge-member and said stud, so that the weight of the typewriter will place said resilient material under tension, and a cushioning collar interposed between said stud and said bridge-member, so as to dampen sideward movement and prevent chattering contact.

4. A non-resonant mounting for a typewriter, comprising a stud attachable to a typewriter to depend therefrom and having an annular shoulder projecting normally from said stud, a disk having an aperture admitting said stud and disposed to overlie said annular shoulder in parallelism therewith, means for detachably supporting said disk, said means presenting guide surfaces adjacent the periphery of said shoulder to limit lateral movement of said stud, and a

resilient ring embracing said stud and interposed between said shoulder and said disk for tensioning in a vertical direction only by the load of the typewriter.

5. A non-resonant mounting for a typewriter, comprising a stud attachable to a typewriter to depend therefrom and having an annular shoulder projecting at right angles from said stud, a base having upstanding walls closely surrounding the periphery of said shoulder to guide same and having a disk closely surrounding said stud and disposed to overlie the annular shoulder of said stud in parallelism therewith, and a resilient ring embracing said stud and interposed between said shoulder and said disk for tensioning in a vertical direction only by the load of the typewriter.

6. A non-resonant mounting for a typewriter, comprising a stud attachable to a typewriter to depend therefrom and having an annular shoulder projecting normally from said stud, a disk having an aperture closely surrounding said stud and disposed to overlie the annular shoulder of said stud in parallelism therewith, means for supporting said disk, a resilient ring embracing said stud and interposed between said shoulder and said disk for tensioning in a vertical direction by the load of the typewriter, and a resilient collar lining the aperture of said disk to cushion said stud against lateral movement.

7. A non-resonant mounting for a typewriter, comprising a stud for threadedly engaging a typewriter to depend therefrom and having an annular shoulder projecting normally from the axis of said stud, a cylindrical cup having side walls adjacent the periphery of said shoulder to limit lateral movement of said stud, a disk superposed on said cup and surrounding said stud to overlie the annular shoulder thereof, and a resilient ring interposed between said shoulder and said disk for tensioning in a vertical direction by the load of the typewriter, said cup having a substantially closed bottom portion defining an aperture for access to said stud in installing the composite mounting on a typewriter.

8. A non-resonant mounting for a typewriter, comprising a stud attachable to a typewriter to depend therefrom and having an annular shoulder projecting normally from said stud, a cup-like housing presenting upstanding side walls disposed adjacent the periphery of said shoulder to limit lateral movement of said stud and terminating in a rim, a disk having releasable engagement with said cup rim for assembly, and overlying said shoulder in parallelism therewith, and a resilient ring secured to said disk and shoulder for yieldable support of the typewriter on said stud.

9. Means for holding a typewriter in floating suspension on a platform for isolation of sound vibrations within the typewriter, said holding means comprising a plurality of units for collectively suspending the load of the typewriter on the platform, each of said units including a resilient member tensioned by the load of the typewriter, and a resilient element interposed between the typewriter and platform intermediate said units and stressed in tension, whereby said element may tend to further tension the resilient elements of said units to coercively isolate sound vibrations of the typewriter from transmission to the platform.

10. Means for holding a typewriter in floating suspension on a platform for isolation of sound vibrations within the typewriter, said holding

means comprising a plurality of units for collectively suspending the load of the typewriter on the platform, each of said units including a resilient member tensioned by the load of the typewriter, and a resilient element consisting of a block of rubber interposed between the typewriter and platform intermediate said units and

stressed in tension, whereby said element may tend to further tension the resilient elements of said units to coercively isolate sound vibrations of the typewriter from transmission to the platform.
